UNITED STATES PATENT OFFICE.

GEORGE FREDERICK WYNNE, OF MINERA, NEAR WREXHAM, COUNTY OF DENBIGH, ASSIGNOR TO THOMAS ROWLAND JORDAN AND ROBERT E. COMMANS, OF LONDON, ENGLAND.

ROCK-DRILL.

SPECIFICATION forming part of Letters Patent No. 314,213, dated March 17, 1885.

Application filed December 13, 1884. (No model.) Patented in England February 24, 1882, No. 903.

To all whom it may concern:

Be it known that I, GEORGE FREDERICK WYNNE, a subject of the Queen of Great Britain, residing at Minera, near Wrexham, in the county of Denbigh, and Kingdom of Great Britain, have invented certain new and useful Improvements in Rock-Drills; and I do hereby declare the following to be a full, clear, and exact description of the invention, such as will enable others skilled in the art to which it appertains to make and use the same.

This invention relates to improvements in double-acting rock-boring machines or drills whereby the compressed air or steam is alternately admitted into opposite ends of the cylinder through ports and passages in the gland and piston-rod.

In carrying out my invention I employ a cylinder of suitable length, near the center of which is located an annular exhaust-port, and into which is fitted a piston the piston-rod of which passes through a gland of peculiar construction, as hereinafter described. Inside the before-mentioned gland is an annular groove which is in communication with the supply-pipe, and in which the motive fluid is always pressing around the piston-rod. From the top of the piston and piston-rod a hole is bored centrally, and at a suitable point in the piston-rod holes are drilled radially, communicating with it, forming the passage to the top end of the cylinder, and longitudinal recesses are also formed on a portion of the periphery of the upper end of the piston-rod, said recesses forming the passage for the motive fluid to the lower end of the cylinder.

By this construction and arrangement, if the piston be in such a position that the radial holes in the piston-rod are in communication with the annular space in the gland, the motive fluid will pass into the top end of the cylinder, and will force it down until the before-mentioned longitudinal recesses are brought into communication with the annular space in the gland, so as to raise it in the opposite direction to that hereinbefore described, and so on.

The exhaust takes place from the top end

of the cylinder through the radial openings in the piston-rod as these in the downward movement of the piston come outside the before-mentioned gland, and from the bottom end of the cylinder through the annular port of very large area.

The twisting arrangement, the cradle, feed-screw, and tool-holder are substantially the same as those now generally employed for this class of rock-boring machines.

In order to enable my invention to be better understood, I will proceed to describe the same by reference to the accompanying drawings, in which—

Figure 1 is a longitudinal section of a rock-drill constructed according to my invention, and Fig. 2 is a transverse section of the same through the gland at Y Z, Fig. 1.

Similar letters in both the figures represent similar parts.

O is the cylinder, P the piston, R the piston-rod, and H the gland. The piston P and piston-rod R are bored out centrally at C; and B are the radial openings made from the outside of the piston-rod R, and communicating with the said central boring, C. F are the longitudinal recesses made in the upper end of the piston-rod. A' is the annular groove or space in the gland H, and A is the entrance for the motive fluid.

The operation is as follows: If the compressed air or other fluid be admitted through A into the annular space A' in the gland H, and the piston P be moved in the cylinder toward D, so that the radial openings B are brought into communication with the annular space A', the motive fluid will be admitted through the central passage, C, to the top side of the piston, and will cause the piston to move in the direction of the arrow z until the longitudinal recesses F are brought into communication with the before-described annular space A', when the motive fluid will be admitted to the bottom side of the piston, and will cause it to move upward in the direction of D. The exhaust takes place through the annular port G in the cylinder as it becomes uncovered by the piston going back-

ward and forward over it. The exhaust also takes place through the radial openings B in the piston-rod as they, in the downward movement of the piston, come outside of the gland H.

5 Having thus described my invention, what I claim, and desire to secure by Letters Patent, is—

1. In a rock-drill, the combination, with the cylinder O, having the annular exhaust-port G, of the hollow piston P, hollow piston-rod R, having external longitudinal recesses, F, and radial openings B, and the gland H, having the annular space A', communicating with the motive-fluid-supply pipe, substantially as shown and described.

2. In a rock-drill, the combination, with the cylinder O, having a central exhaust, of a hollow piston and piston-rod, the latter being provided with inlet-openings entering the hollow piston-rod space, and with longitudinal external recesses, and a gland surrounding the piston-rod and connecting with the motive-fluid supply, substantially as shown and described.

GEORGE FREDERICK WYNNE.

In presence of—

WILLIAM POTTER,

R. POTTER,

Both of Wrexham.
